POURING APERTURE CARTON

Arthur J. Weiss, River Edge Manor, N. J., assignor
to Robert Gair Company, Inc., New York, N. Y.,
a corporation of Delaware

Application January 6, 1937, Serial No. 119,169

4 Claims. (Cl. 229—17)

The present invention relates to paper board cartons and has for its object an improvement in pouring cartons in which a pouring aperture may be made in the carton for permitting dry 5 pulverulent or granular contents thereof, to be emptied from the carton.

In the present embodiment, the carton may be made up of a single sheet of paper board and 10 may comprise the usual body forming panels set up to form a rectangular carton with flaps extending from each end of each panel to form top and bottom closure flaps.

One of the features of advantage of one of the 15 closures shown herein is that after opening the same, it may be tucked into its original position to be held as a reopenable and reclosable pouring tuck flap.

Other advantages will be noted as the herein disclosure proceeds and it will be obvious that 20 modifications may be made in the structure hereof or in without departing from the spirit hereof or the scope of the appended claims.

In the drawing—

Fig. 1 is a fragmentary, perspective view of one 25 embodiment of the present device, closed;

Fig. 2 is a view similar to Fig. 1, showing the sealed closure open end;

Fig. 3 shows an alternate, preferred form of 30 closure in fragmentary, perspective view;

Fig. 4 is a fragmentary perspective view of the carton of Fig. 3 tipped to a pouring angle with its seal broken;

Fig. 5 is a fragmentary plan view of the blank 35 of the carton of Figs. 1 and 2;

Fig. 6 is a fragmentary plan view of the blank 40 of the carton of Figs. 3 and 4; and

Fig. 7 is a fragmentary sectional view taken on line 7—7, Fig. 3, looking in the direction of the arrows.

The present pouring closure is developed about 45 one of the corners of the carton, and as shown in the drawing, the carton may be of the standard form previously noted.

The cooperating parts of the closure involve at 50 least two adjacent angular walls of the carton which forms a corner thereof and at least two of the coacting closure flaps, when in carton assembly.

In Figs. 1 and 5, the adjacent side panels 1, 2 55 and 3 have extending closure flaps 4, 5 and 6 respectively. Closure flap 5 is scored from its narrow panel 2 by a common score line 7, which also scores flaps 4 and 6 from panels 1 and 3, as in Fig. 5. As shown in Fig. 5, flaps 4, 5 and 6 are defined from one another by cuts 20—20, which

extend from the outer edges of said flaps down to the score line 7, and thus the said flaps are as customary, each being independently foldable upon one another, after gluing.

Flap 4, Fig. 5 has its edge, adjacent the cut 20 5 and flap 5, provided with a semi-circular cut-out 12. Likewise the flap 6, adjacent its cut 20 and the flap 5, has its edge provided with a semi-circular cut-out 13. It will be seen that the flap 5 and its appurtenant panel 2, Fig. 5, is provided with a circular pick-out piece 10 defined half and half out of each portions 2 and 5, by a circular line of perforations, such circular pick-out piece spanning the score line 7, so that when the carton is formed and closed in rectangular assembly as in Fig. 1, with all flaps 4, 5, 6 and the opposite mate flap to 5, not shown, are glued to one another the pick-out piece 10 is formed on the corner junction of flap 5 and panel 2.

The flap 5 and its companion flap, not shown 20 10 are first closed down, and then flaps 4 and 5 are glued on their underfaces and closed down, with the circular cut-outs 12 and 13 bordering that half section of the piece 10 which is in flap 5. 15 Thus cut-outs 12 and 13 provide a finger space 25 about the half section of the cut-out piece 10.

To open this particular form of package the user grasps the angularly disposed pick-out piece 10 between a finger and thumb, and pinches it, thus causing the pick-out piece to break at its 30 line of weakening 11, the removed section 10 then being discarded, leaving the package with the opening T, as in Fig. 2, ready for pouring out the contents.

In the alternate form shown in Figs. 3, 4 and 35 6, in which like portions of the carton bear like indices for parts similar to those of Figs. 1, 2 and 4, the flap 5 and the panel 2, Fig. 6, have a pick-out tuck flap 14, partially defined thereon by a cut-through semi-circular line 16 on flap 40 5, the ends of said semi-circular cut ending short of the score line 7, and being there joined by two perforated weakened lines 15—15, which extend past the score line 7, and down a suitable distance onto panel 2, where they end at a traversing score line 8.

That portion of the tuck flap 14 located on the panel 5 and about the margins thereof is coated with a glue resist 17, such as wax or ink, so that when the flaps 4, 5, and 6 are in glued assembly 50 the end of the tuck flap 14 and its margin as overlaid by glued flap 4, is free from glued attachment to flap 4. As the finger opening cut-outs 18 and 19 on closing flaps 4 and 6 are smaller 55 in dimension than the rounded end of tuck flap 55

14, and the circular end of the flap 14, Fig. 3, shown dotted, extends beyond the finger cuts 18-19, the semi-circular cut-through 16 is covered by the flap 4, which thus prevents sifting 5 of the contents through the semi-circular cut 16. The overlay of the flaps 4 and 6 on the tuck flap 14 is shown in Fig. 7.

To open this package, after the carton has been filled and glue assembled, the corner formed, 10 perforated and cut flap 14 is grasped between a thumb and finger and pinched, thus breaking the lines of weakened resistance 18-18, and the resultant flap 6, Fig. 4, is pulled out and bent on its score line S, after which, when the desired 15 contents are poured out, the flap may then be tucked back into its original position as in Fig. 7, under flap 4. Thus this latter flap not only renders the contents of the package accessible, but it also performs the function of reclosable tuck flap, to close the pouring aperture and protect the 20 remaining contents of the carton.

Thus it will be noted that the present pouring means are created in a flat one piece blank, without added parts and wholly within the 25 confines of the blank itself.

Having thus described the invention what is claimed is:

1. A carton comprising a front wall having thereon a flap forming an under end closure member, said wall and member having therein a tear out tuck to provide a pouring opening; said tuck having a base part in the wall and a free terminal and marginal part in said member, there being weakened lines on opposite sides 35 of said parts and there being a cut extending from the ends of the lines around the terminal; and two side walls having thereon flaps forming upper members of the closure, said upper members having therein finger spaces which register above said marginal part, the contour of the 40 space boundaries being such as to cover the said lines in the marginal part, said cut being then covered in sift proof relation by the flaps thereat.

2. A carton comprising a front wall having thereon a flap forming an inner under end closure member, said wall and inner member having therein a tear-out tuckable flap to provide a pouring aperture; said tuckable flap having a hinged base part in said wall and a free terminal 45 and marginal part positioned in said inner member, there being spaced lines of weakness defining said hinged base part from said wall, there being a cut extending from the lines of weakness around the terminal and two side walls having flaps thereon forming upper members of the clo- 50

sure, said upper members having therein finger spaces which register above and over said marginal part, the contour of the space boundaries being such as to expose a portion of the marginal part, the cut portion thereof being covered in 5 sift proof relation by the upper flaps, said upper flaps, after the tuckable flap has been opened, forming a seat for the marginal portion of said tuckable flap, to receive and hold the same in its original closure position when closed. 10

3. The combination in a carton, having a front wall, of an under closure flap on said front wall, which, when in closed position forms a corner with said wall, a tear out portion on said corner defined by lines of weakness on said wall and 15 flap, the part of the tear out portion on said flap being coated on its face and beyond the margins of its line of weakness with a glue resist, and upper side closing flaps on said carton which are superposed upon the under closure flap 20 and glued thereto, said closing flaps being provided with finger spaces which are superposed over the coated face of the tear out portion, the edges of the finger spaces extending over the line of weakness of the coated face of the 25 tear out portion in a sift preventing manner, as and for the purpose described.

4. The combination in a carton, having a front wall, of an under closure flap on said front wall, which, when in closed position forms a corner 30 with said wall, a tear out portion on said corner for forming a closable corner pouring aperture when broken and defined by lines of weakness on said wall and flap, the part of the tear out portion on said flap being coated on its face 35 and beyond the margins of its line of weakness with a glue resist, whereby to maintain said tear out portion on said flap portion detachably free of glue and upper side closing flaps on said carton which are superposed upon the under closure 40 flap and glued thereto, said closing flaps being provided with finger spaces which are superposed over the coated face of the tear out portion, whereby to afford manual access to the tear out flap portion, the edges of the finger spaces extending over the line of weakness of the coated 45 face of the tear out portion in a sift preventing manner and forming a superposed retuck seat for the flap tear out portion whereby the flap tear out portion when reclosed, will occupy its 50 original aperture and seat in said closure flap, and under said superposed flaps, as and for the purpose described.

ARTHUR J. WEISS.
